RECEPTACLE

Sahatiel G. Mandalian, North Attleboro, Mass.

Application August 22, 1935, Serial No. 37,326

7 Claims. (Cl. 132—82)

My invention relates to receptacles and to the component parts of receptacles of the metallic-mesh pouch type adapted to accommodate compacts, cosmetics, or other toilet articles.

5 In articles of the mesh pouch type difficulty has been encountered in satisfactorily securing the mesh fabric to the clamping ring constituting the rim of the receptacle.

It was sought to effect this end by employing a 10 clamping ring with a narrow upper downwardly curled flange, and a broad inwardly projecting lower flange that resulted in unduly restricting the capacity of the resulting receptacle by a retracted neck portion. Auxiliary to the clamping 15 ring was employed a transversely angular ring comprising a horizontal annular plate resting upon the extended portion of the lower flange of the clamping ring, and a depending integral cylindrical plate provided with an annular disposed series of attaching holes.

The rigid character of the auxiliary ring made it necessary to first form the lower flange of the clamping ring, then lay the upper plate of the auxiliary ring upon said lower flange, and later 20 complete the formation of the clamping ring by downwardly bending thereover, upon an intervening lining member, the material forming the ultimate upper flange of the clamping ring. This piecemeal method of ring formation was slow and 25 complicated.

The depending perforated cylindrical plate of the auxiliary ring lessened the area otherwise utilizable by the ornamental ring mesh, and the rigid character of the plate tended to cramp the 30 mesh adjacent the attaching rings of the latter.

The essential objects of my invention are to 35 overcome the above recited deficiencies and disadvantages; to facilitate the assemblage of the parts; and to provide a metallic mesh pouch of 40 such a construction as to enable the usual so called lining to be dispensed with when and if desired.

With the above ends in view, together with other advantageous features hereinafter apparent 45 and to be adverted to, my invention consists in such parts and in such combinations of parts as fall within the scope of the appended claims.

In the accompanying drawing,—

Figures 1 and 2 are a side elevation and top 50 plan view respectively of a receptacle of the metallic mesh type in which my invention is incorporated,

Figure 3, an enlarged section of the same taken on line 3—3 of Figure 2,

55 Figure 4, a side elevation of the container,

Figure 5, an enlarged fragmentary plan view of the same,

Figure 6, an enlarged side elevation of a portion of the container, and

Figure 7, a section of a modified form of my 5 invention taken on a line corresponding to line 3—3 of Figure 2.

In the construction illustrated 10 represents a receptacle of the metallic mesh type wherein 12 is a transversely U shaped retaining ring or rim, 10 comprising a peripheral portion or back 14 and horizontally disposed, flat, guiding lips 15 cooperating with the back to form an annular cavity 16.

The receptacle is preferably provided with a 15 closure. In the present instance the closure comprises a circular convex cover 17 resting upon the ring 12 and having integral peripheral hinge sleeves 18 embracing a pivot pin 19 fixed to the retaining ring. A catch 22 consists of an integral 20 curved tongue upon the edge of the cover engageable with the retaining ring. An arched thumb bearing 24 is fixed to the latter to assist the manual manipulation of the catch.

In this instance a circular frame 26 has its back 25 27 fixed to the cover 17, and its side 28 surrounding a mirror 29 and a backing 30. A retaining ring 31 frictionally embracing the side of the frame overlaps the margin of the mirror, which extends into the receptacle when the cover is 30 closed.

A container member 34, shown detached in Figure 4, includes a substantially flat carrier frame 35 comprising a circular series of radially disposed, integrally connected, interspaced loops 36, 35 from which depends a horizontally disposed, resilient, spiral, suspension ring 37 to which it is attached by the loose interengagement of the constituent coils 38 of the suspension ring with the successive loops 36 of the frame, through which 40 the coils are threaded. In threading, the coils 38 also successively pass loosely through the several adjacent rings or links 39 constituting the uppermost row of links of a flexible mesh pouch or bag 40. The mesh is preferably metallic and, as 45 shown in Figure 6, is of the type of mesh fabric known as "coat of mail." Other usual or preferred types of mesh fabric or other suitable material may be employed.

The container 34 with its three elements as- 50 sembled as described is suited for facile engagement with the ring 12. This is effected by manually compressing the frame portion 35, whose maximum diameter exceeds the minimum diameter of the ring 12, and is radially, circularly, 55

and transversely resilient, to admit its periphery to the cavity 16 of the ring 12, and then releasing said frame portion to permit the latter to impel itself instantly and firmly in the cavity, with its inner margin projecting slightly from the lips. Hence no clamping or compression of the guide lips 15 or other mechanical steps or structures for securing the container 34 is necessary to insure the security of its engagement with the ring 12.

10 The described interengagement completes the receptacle which is adapted to receive any desired contents. In this instance the contents consists of a powder compact 43 surmounted by a powder puff 44 as shown in Figure 3.

15 Not only does the resilient spiral suspension ring 37 facilitate the interengagement of the carrier frame 35 with the bag 40, but permits movement of the bag margin both radially and circularly, thus relieving strain upon the fabric and preventing wrinkles or gatherings of the latter at and along its attached edge.

20 When any of the contents of the bag are so fine or comminuted as to sift through the receptacle the latter may be rendered impervious by the insertion of a lining member or internal bag 46 of a leather fabric, or other flexible material into the receptacle, as shown in Figure 7. The bag 46 comprises a body portion 47, and an annular horizontal lip 48 at its top overlapping 25 the carrier frame 35 within the retaining ring 12. As herein shown the contents of the receptacle includes loose powder 50.

I claim:—

1. In an article of the class described, a retaining ring provided with an annular recess, an annular resilient carrier frame in the recess, a bag, and a spiral suspension ring laterally engaging both the frame and the bag.

35 2. In an article of the class described, a horizontal retaining ring comprising a back and inwardly directed guide lips, an annular radially

compressible carrier frame of normally greater diameter than the minimum diameter of the ring engageable with the ring between the lips, and a mesh bag supported by the carrier frame.

3. In an article of the class described, a retaining ring provided with an annular recess, a carrier frame comprising a circular series of radially disposed loops extending into the recess, a metallic mesh bag, and a spiral suspension ring comprising coils passing through the loops 10 and secured to the bag.

4. In an article of the class described, a retaining ring provided with a horizontal recess, a resilient carrier frame comprising a series of radial loops mounted in the recess, a circularly 15 yielding suspension ring comprising coils loosely engaging the loops, and a mesh bag provided with a series of openings adapted to receive the loops.

5. In an article of the class described, a retaining ring, a carrier frame comprising a series 20 of loops supported by said ring, a metallic mesh bag including a circular row of attaching rings, and a suspension ring comprising coils engaging the loops and the attaching rings.

6. As a new article of manufacture, a container for a receptacle, said container including a resilient carrier frame comprising a circular series of loops, a metallic mesh bag comprising a series of attaching rings, and a spiral suspension ring comprising coils successively engaging 30 the loops and the attaching rings.

7. In an article of the class described, a retaining ring provided with an annular recess, a carrier frame in the recess, a metallic mesh bag, a spiral suspension ring engaging both the frame 35 and bag, and a lining bag within the mesh bag and the suspension ring including a lip extending into the recess and overlapping the carrier frame.

SAHATIEL G. MANDALIAN. 40
